The ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image thereof; and,

FIG. 3 is a third image thereof.

The broken lines are for environmental purposes only and form no part of the claimed design.

The appearance of the image transitions sequentially between the images shown in FIGS. 1-3. The process or period in which one image transitions to another forms no part of the claimed design. The broken lines shown in the drawings illustrate an environmental monitor and portions of the display screen or a portion thereof with animated graphical user interface that forms no part of the claimed design.
